UNITED STATES PATENT OFFICE.

NORMAN P. DANA, OF PORTLAND, MAINE.

MEMORANDUM DESK CALENDAR.

Application filed April 12, 1923. Serial No. 631,553.

My invention relates to memorandum desk calendars constructed for making memoranda and the like and the particular purpose of the invention is to construct a pad arranged with a means of holding a series of strips or elongated cards divided off into spaces, one for each day of the week. The pad is designed to be so arranged that a plurality of strips preferably three in number, each representing one week will at all times be in sight.

Of the three weekly cards in sight, one will present the current week, one the week last past and one the next coming week. The cards are preferably printed on both sides so that with 26 cards using both sides of each card, the entire year of 52 weeks will be covered.

A storage space is provided for in the device in which the cards as fast as they are used are moved along from one week to the next and then filed in the storage space where they are arranged in their proper order.

I have illustrated my invention in the accompanying drawing in which the construction of the device as I prefer to make it and the manner in which it is used is fully illustrated.

Referring to the drawing:—

Fig. 1 is a perspective view of my desk pad ready for use,

Fig. 2 is a perspective view with the card holding plate raised to show the interior,

Fig. 3 is an end elevation with the card holding plate in the same position as shown in Fig. 2, and with a portion of the cards tilted forward.

Fig. 4 is a section taken on the line 4—4 of Fig. 1 and,

Fig. 5 is one of the cards bent to show the printing on opposite sides.

Referring to the drawing, 1 represents the card-holding plate which forms the upper surface of the pad. The plate 1 is large enough to support three elongating cards 2, 3, and 4, each of which is removably held in a pocket 5 from which it may be readily removed. As shown, each pocket is formed of a recess struck up from the material of the plate which is preferably made of sheet metal, a recess being formed at each end of the card. The end of the card is held in place by being slipped into the recess 5.

The card, if desired, can be removed from the pocket 5 by being sprung up in the mid-

dle and it can be replaced by being bent in the center, the ends inserted in the recesses 5 and the card flattened.

As here shown, the holder is made wide enough for three cards, two of which are held in pockets on the pad proper while the third is held on a rearward extension 6 which is bent upwardly from the rear end of the front portion of the pad proper to form an inclined extension where the card will be plainly in sight.

Each of the cards 2, 3, and 4 and the other 23 cards which constitute the entire number usually necessary are divided off into seven spaces to represent the days of the week, each being also numbered to correspond to the days of the month.

The cards 2, 3, and 4 and the pockets 5 in which they are held are arranged in line from front to rear of the pad so that the daily spaces will come one above the other in line and the days of the week are indicated by a strip 7 which is secured by rivets 8 or otherwise along the upper edge of the extension 6. They are thus arranged to head the line of days as printed on the faces of the cards. The strip 7 is marked from Sunday to Saturday indicated by the usual abbreviations.

The card-holding plate 1 with its rear extension 6 is held in a position sloping slightly forward, and the plate support 1 is pivoted to the rear portion of the support by pivots 11. The support is made up of a rear member 9 and two end members 10. The upper edges incline forward to give a forwardly inclining surface for the pad. The rear member 9 and the end member 10 are made up of metal plates integral with each other having their lower portions bent inward to form flanges 9' and 10' which provide supporting surfaces to support the several record cards 2, 3, 4, etc. all marked 12 when shown inside the pad proper where they are stored.

The surfaces of the flanges 10' and 9' are covered with rubber, felt or other frictional material which will hold the lower edges of the cards 12 from slipping when they are stored in the inside of the pad.

The pad is used as follows:—

The three cards 2, 3, and 4 are placed in their corresponding pockets 5 coming in line from front to rear with the days of the week in line over each other.

Thus, card 3 indicates the current week,

card 4 the past week and card 2 the next week. The user thus has three weeks under his eye and can make memoranda or consult memoranda made for that time.

- 5 At the expiration of the present week, card 2 which indicates next week is moved up to the place occupied by card 3 and becomes the current week for the next week's operation. Card 3 is moved upward to the 10 position of card 4 and card 4 is added to the rear end of cards 12 stored beneath. By lifting the card-holding plate, access is given to the space beneath and the spare cards 12 may be placed in position or removed therefrom.

Cards 12 are arranged in regular order from the rear toward the front, each card as it is inserted being placed in the rear and the card which is taken from the storage 20 place beneath is taken from the front portion of the stored cards and placed in the position of card 2 in place of card 2.

The cards 12 have their lower edges resting on the two extensions 10' and 9', the 25 surfaces of which are covered with felt or rubber or other frictional material so that the cards when placed together will occupy a leaning or backwardly inclined position. By manipulating them properly, they can be tilted forward to a forwardly inclined position and any desired card for the entire year 30 may be consulted or receive memoranda. The cards tilted forward are read in their reverse position as shown in Fig. 5.

35 Each of the record cards is printed on both sides, the figures and letters being so arranged that when the card is reversed it will be seen in an upright position, that is to say, the figures and letters on one side are reversed in respect to those on the opposite side as shown in Fig. 5.

For convenience of arrangement, weeks indicated on the opposite side of each card are exactly 26 weeks apart or one-half year. For instance, the week beginning January 1st, if an even week happens to begin at that time would have on its opposite side the week beginning July 1st which would be exactly six months in advance.

By this arrangement, the cards are kept 50 regularly arranged in the storage space and the three cards which represent three adjacent weeks are regularly moved into place from the cards in the storage space without being disturbed.

55 It will be seen that when the cards are in their normal position entries may be made from one day to two weeks ahead of any given date.

I claim:—

1. A memorandum calendar including a card-holding plate, a support to the rear portion of which said plate is pivoted, said support consisting of a back piece and two end pieces, each having an inwardly projecting card-supporting flange, each flange having a frictional surface for holding the loose cards in position and card-holding pockets formed in said plate.

60 2. A memorandum calendar including a card-holding plate, the rear portion of which is bent or inclined upwardly, a plate support to the rear portion of which said plate is pivoted, said support consisting of a back piece and two end pieces, each piece 65 having an inwardly extending card-supporting flange, said flanges having frictional surfaces; and pockets supported on said plate for removably holding elongated memorandum cards.

70 NORMAN P. DANA.
